DESIGN FOR A FRAME FOR DISPLAY CARDS

Fred J. Signet, Venice, Calif.

Application March 19, 1938, Serial No. 75,974

Term of patent 7 years

To all whom it may concern:

Be it known that Fred J. Signet, a citizen of the United States, residing at Venice, in the county of Los Angeles and State of California, has invented a new, original, and ornamental Design for a Frame for Display Cards, of which the following is a specification, reference being had to the accompanying drawing forming part thereof.

Figure 1 is a front view of the frame for display cards showing my new design.

Figure 2 is a side view thereof.
Figure 3 is a rear view thereof.
Figure 4 is an end view thereof.
Figure 5 is a sectional view on line 5—5 of Figure 1.

I claim:

The ornamental design for a frame for display cards, as shown.

FRED J. SIGNET.
